UNITED STATES PATENT OFFICE.

JAMES W. CALTA, OF PLATTE, SOUTH DAKOTA.

ENGINE-PISTON.

1,373,714.

Specification of Letters Patent. Patented Apr. 5, 1921.

Application filed May 19, 1919. Serial No. 298,180.

To all whom it may concern:

Be it known that I, JAMES W. CALTA, a citizen of the United States, residing at Platte, county of Charles Mix, and State of 5 South Dakota, have invented certain new and useful Improvements in Engine-Pistons, of which the following is a specification.

My invention relates to improvements in pistons and cylinders of internal combustion 10 engines, and it consists in the combinations, constructions and arrangements herein described and claimed.

An object of my invention is to provide a piston having means for preventing the 15 working of the oil up into the explosion chamber, said means comprising a plurality of recesses forming pockets which may contain a sealing compound.

A further object of my invention is to 20 provide means for retaining in the explosion chamber any unconsumed fuel oil, and for preventing the latter from working down past the piston into the crank case. In order to carry out the last-named object, I make 25 the head of the piston dish-shaped, and also provide the explosion chamber with means for retaining unconsumed liquid fuel, as will be explained later.

Other objects and advantages will appear 30 in the following specification, and the novel features of the invention will be particularly pointed out in the appended claims.

My invention is illustrated in the accompanying drawings, forming part of this application, in which:

Figure 1 is a sectional view through the piston and cylinder; and

Fig. 2 is a side elevation of the piston.

In carrying out my invention I provide 40 a piston 1 having the usual piston rings 2, 3, 4 and 5. The head of the piston is dished, as shown at 5^x.

Just above each piston ring is a recess or 45 pocket 2', 3', 4' and 5' extending around the circumference of the piston. These recesses are all formed with a sharp curve at the upper end, the lower ends tapering gradually to the outer edge of the piston. The recesses or pockets thus formed may be made 50 in a lathe, or may be partly formed when the piston is cast, and then trued up.

In Fig. 1, I have shown a section through the explosion chamber, and it will be noted that there is an annular trough 9 at the outer 55 edge of the explosion chamber 10.

From the foregoing description of the

various parts of the device, the operation thereof may be readily understood. The recesses, or pockets, 2', 3', 4' and 5' are designed to be filled with a sealing compound 60 11, such as that described in my prior application, Serial No. 259410. This sealing compound consists of a mixture of refractory and lubricating materials, such as asbestos fiber, graphite, soapstone, mica and plum- 65 bago, and it has the double function of preventing the working of the oil from the crank case up past the piston, or the working of the liquid fuel downwardly into the crank case, and it also provides a lubricat- 70 ing means in itself. The composition, as stated, forms the subject of another application, the present application being directed to the means by which the piston is sealed 75 and partly lubricated. In internal combustion engines which are fed with too rich a mixture, there is always a certain portion of the mixture which is unconsumed. This tends to condense and to work down past the piston rings into the crank case, thus 80 wasting the liquid fuel and interfering with the proper lubrication of the piston. The present invention is designed to obviate this danger. The dish-shaped recess 5^x in the head of the piston, holds any such condensed 85 fuel, the condensation taking place more rapidly when the engine is cold, as when it is first started. In subsequent explosions, this fuel is consumed instead of being 90 wasted. That portion of the condensed fuel, 90 which is condensed by coming in contact with the cold walls of the explosion chamber, runs into the trough 9, where it is available for use with subsequent explosions.

The dishing of the piston head also serves 95 another purpose, viz., as a receptacle for any liquid fuel which may be injected into the cylinders when the engine is being primed.

The invention as described above, also 100 prevents the passage of lubricating oil upwardly, or of the liquid fuel downwardly through the joint or journal of the wrist pin. These parts, as is well known, tend to wear so as to permit the passage of oil or 105 liquid fuel or gas unless means, as in the present invention, are provided to prevent it.

Other advantages resulting from the arrangement described herein, such as the fact 110 that the cylinders will be kept smooth and clean, that the explosive is prevented from

passing by the rings through the grooves, said lubricating oil is prevented from entering the combustion chamber and coming in contact with the spark plug and ruining the latter. The arrangement causes the engine to fire more evenly and uniformly because no oil can get to the spark plug. Since the water does not heat up as in the ordinary type of engine, less water is necessary. Less gasoline is necessary and the power of the motor is increased; less lubricating oil is necessary. Since the explosives cannot get onto the cylinder walls and piston rings, the latter are kept cool. The composition carried in the recesses keeps the cylinder and piston lubricated. The composition tends to expand the rings as they wear, and hence obviates the necessity of buying new ones. This composition tends to work into the pores in the rings and in the walls of the cylinders, making the engine run smoother. By sealing the rings in the pistons it will overcome many difficulties. The arrangement also prevents the carbon from getting into the crank case and destroying the lubricating oil.

Since lubricating oil is kept out of the explosive chamber by the sealing means described, it prevents a blue smoke from going out at the recesses. When the cylinders are worn out of shape, or are not properly cylindrical the material comprising the sealing compound will overcome the difficulty ordinarily experienced by worn cylinders. In this connection it will be noted that the wrist pin 18 being arranged at the upper end of the piston, a relatively longer connecting rod will be used. By reason of the

relatively great length of the connecting rods used, the wear on the pistons and rings and on the cylinders will be reduced to a minimum, and hence the danger of wearing the cylinders into an oval or egg shape will be practically overcome, since the piston rings will not slap against the sides of the cylinders. This ring will also insure a smoother running engine, and will materially increase the power of the engine.

I claim:

1. A piston for internal combustion engines including a body portion having a series of annular grooves in its exterior face and piston rings in said grooves, and annular tapering recesses in the exterior face of the piston, the tapering walls of the recesses gradually approaching the circumference of the piston body and terminating in and coinciding with one outer corner of said grooves.

2. A piston for internal combustion engines having a plurality of piston rings and a recess above each piston ring, each of said recesses being tapered outwardly toward the exterior of the piston on the side of the recess toward the adjacent piston ring.

3. A piston for internal combustion engines having a plurality of piston rings, said piston being provided with a circumferential groove disposed immediately above each piston ring, the bottoms of the grooves adjacent to the piston ring being relatively shallow, and each of said grooves being adapted to contain a lubricating sealing material.

JAMES W. CALTA.
